Primary Examiner — Ricky Pham(74) *Attorney, Agent, or Firm* — Cramer Patent & Design
Pllc; Aaron R. Cramer(57) **CLAIM**

The ornamental design for a cookware set, as shown and described.

DESCRIPTION

FIG. 1 is a perspective top rear left view of a cookware set, including a lid feature, a first insert feature, a second insert feature, and a container feature, showing our new design; FIG. 2 is a perspective top front right view of a cookware set thereof;

FIG. 3 is a front elevation view thereof;
FIG. 4 is a rear elevation view thereof;
FIG. 5 is a right elevation view thereof;
FIG. 6 is a left elevation view thereof;
FIG. 7 is a top plan view thereof; and,
FIG. 8 is a bottom plan view thereof.

The broken lines at the bottom of the first insert feature and second insert feature indicate a nesting means and form no part of the claimed design.

The broken lines representing the fasteners on the lid feature and the container feature form no part of the claimed design.
